THOMAS L. LOWE, OF DEVON, CONNECTICUT, ASSIGNOR TO THE LOWE MACHINERY COMPANY, OF BRIDGEPORT, CONNECTICUT, A CORPORATION OF CONNECTICUT.

AUTOMATIC FEEDER FOR LAUNDRY MACHINERY.

Application filed February 5, 1925. Serial No. 7,050.

The present invention relates to an automatic feeder for laundry drying, ironing and pressing machines and has for an object to provide a machine of this character adapted to be employed in connection with an ironing machine in a manner to greatly add to its efficiency and capacity.

The methods heretofore employed for feeding articles of laundry to an ironer consisted in manually placing the articles upon the moving apron of the ironer, several operators being usually employed for this purpose and who stand in front of the machine as it is continuously operating and place the articles in flat relation upon the moving apron. This method, however, required that the operator work with great rapidity in order to get as many articles as possible in place upon the moving apron, and precluded very close or precise placement of the pieces, with the result that they were very often wrinkled or folded as they moved into the ironer, and much of the ironing space was not utilized inasmuch as the articles could not be placed to the best advantage in the time allowed. It was therefore impossible to operate these ironers with efficiency and in a manner to take advantage of their full potential capacity.

According to the present invention it is proposed to provide a feeding device adapted to be pre-loaded—that is, loaded before being placed into operative feeding relation with the ironer—and which when placed in such relation will automatically feed the pieces with relatively great speed. This, combined with the fact that the feeder permits placement of the pieces in very close relation and to the best advantage, with the parts of each properly disposed relative to each other for ironing will enable the greatest efficiency as to speed and capacity, and the highest quality of work, to be obtained from the ironer. In the usual operation of the device two or more feeders are employed in connection with a single ironer so that while one is feeding to the ironer, another is being loaded, and a substantially continuous operation may thus be carried out.

A further object of the invention is to pro-

vide a machine which will take care of either a small or large number of pieces, and in which the pieces will be subjected to a preliminary smoothing action before feeding into the ironer so that the possibility of the same being crumpled or folded is prevented.

A further object of the invention is to provide a device of this character in which the operator will place the pieces in position upon a portion of the receiving apron while the machine is stationary, and when a number of pieces are so placed the machine will be fed to bring an unloaded portion of the apron into place, these feeding movements being entirely controlled by the operator so that sufficient time will be allowed for the placement of the articles. Some articles, it will be understood, require a greater length of time than others, so that the machine will be variably controlled to allow sufficient time for placement of all kinds of articles. With the previously employed methods this was not possible as the pieces had to be fed upon the apron of the moving machine which moved at a continuous and constant rate of speed.

Other objects are to provide a machine which will be relatively simple in construction, and reliable and positive in operation.

With the above and other objects in view embodiments of the invention are shown in the accompanying drawings, and these embodiments will be hereinafter more fully described with reference thereto, and the invention will be finally pointed out in the claims.

In the drawings:

Fig. 1 is an end elevation of an automatic laundry feeding machine according to the present embodiment of my invention, and in position with relation to the ironing machine to feed laundry thereto;

Fig. 2 is a front elevation of the machine, broken away at the center, and having a part of the conveyer removed from one end portion;

Fig. 3 is a central vertical cross section of the machine, located in front of an ironing machine of the conventional type, and in position to feed laundry thereto;

Fig. 4 is a diagrammatical floor plan view showing a laundry ironing machine and two of the automatic feeders, according to the invention, positioned upon a track upon which they are moved to and from the ironer;

Fig. 5 is an enlarged sectional elevation of a hand operable clutch device for driving the feeding machine in relation to the ironer;

Fig. 6 is an enlarged sectional elevation of a foot operable clutch device for operating the feeder during loading; this operation of the machine being in reverse direction from the operation in relation to the ironer and taking place intermittently;

Fig. 7 is a side elevation of a modified form of the invention, the same being adapted to carry two conveyor aprons instead of one as employed in the first form, the pieces of laundry being fed between the two aprons;

Fig. 8 is a detail view of the forward end of the feed table, with a portion of the apron removed and which is adapted as the pieces are fed into relation with the ironer to insure their removal from the apron and the feeding device; and

Fig. 9 is a detailed sectional view thereof along the line 9—9 of Fig. 8.

Similar reference characters indicate corresponding parts throughout the several figures of the drawings.

Referring to the drawings and more particularly to Fig. 3 thereof, an ironing machine of the conventional type is illustrated diagrammatically and comprises a large cylindrical drum 10 rotatably mounted upon end standards 11 and adapted during operation to be rotated by suitable drive means. An endless apron 12 extends about the drum, first between the outer drum surface and a series of padded rolls 13, 14 and 15 mounted at the lower side of the ironer frame, the feed roll 13 being disposed adjacent the feeding opening to the drum and adapted to guide the apron onto the drum from an adjustably mounted roller 16, the portion of the apron between the rollers 13 and 16 constituting a receiving surface upon which the pieces to be ironed are laid in the usual operation of the ironer. The apron extends about the drum to a point in spaced relation to the roller 13 where it is carried off about a roller 17 and then reversely over rollers 18, 19 and 20 engaging the under side thereof, then over an inset roller 21 engaging the outer side and an adjustably mounted roller 22 engaging the underside, and from which latter roller it passes beneath the rollers 15 and 14 and over the roller 16 into engagement with the drum. Doffer knives 23 engage the surface of the drum at a point slightly spaced from the point at which the apron leaves it and are adapted to prevent the articles from continuing in engagement with the drum, an endless feed apron or conveyor 24 extending

about the roller 17, and fed by suitable rollers 25 and 26, carrying the pieces about the roller 17, from which they are fed upon the apron rearwardly over the rollers 18 and 19 and finally removed onto suitable tables or conveyers as the apron passes over the roller 20. With certain classes of work, as sheets that must be folded, the roller 22 is adapted to be adjusted to the dotted line position shown in Fig. 3 to facilitate this operation.

According to the invention, a pair of tracks 27 and 28 are provided upon the floor in front of the ironer and extend on each side thereof as shown in Fig. 4, the feeding machines, preferably two in number, being mounted on these tracks, and being adapted to be moved from their loading positions or stations at one or the other sides of the ironer to their feeding position or station in front of the

The feeding machine comprises a main frame consisting of horizontal rectangular upper and lower frames 30 and 31 formed of structural channel iron and connected at their corners by vertical supports 32 formed of structural angle iron, the frame being movably supported on the tracks by means of rollers 33 suitably journaled in the lower frame portion 31.

Angularly disposed reinforcing struts or truss bars 34 are connected between the ends of the lower channel irons of the frame at each end and the central portions of the upper channel irons (Fig. 1), and also between the ends of the upper channel irons at the front and rear and the central portions of the lower channel irons (Fig. 2).

At each end of the frame there is provided a central vertically disposed channel bar 35 bolted at its ends to the frame, and at the upper side and centrally at each end there are also mounted channel guide bars 36 in substantially aligned continuation of the bars 35, these bars 36 being bolted at their lower ends to the frame and being supported by a truss bar 37 having a horizontal lower end portion secured to the bars 35 and bolted to the frame and an angular strut portion bent upwardly from the lower end portion to the upper end of the bars 36 where it is bolted. The bars 36 are further supported by truss bars 38 extending from their upper ends to the rear end portions to the upper sides of the frame.

Within the guide bars 35 and 36 there are slidably engaged for vertical movement the respective reduced ends 39 and 40 of apron rolls 41 and 42 of corresponding diameter, the lower roll 41 adapted to rest upon and between feed rolls 43 and 44 having their shafts journaled in suitable bearings 45 and 46 secured upon the lower horizontal end portions of the frame at each side of the central vertical guide bars 35, while the upper roll 42 is

similarly supported upon and between feed rolls 47 and 48 having their shafts journaled in bearings 49 and 50 secured upon the upper horizontal end portions of the frame at each side of the central vertical guide bars 36.

The feed rolls are adapted to be driven at equal rotational or angular speed while the apron rolls, with the apron wound thereon, are adapted to be driven by the feed rolls at equal 10 surface speed but at varying angular speed. For this purpose a large gear 51 is provided upon one end of the roll 43 and adapted to be meshed by drive means, hereinafter more fully described, and upon the other end of 15 this roll there is provided a sprocket gear 52 connecting a sprocket chain 53 with a sprocket gear 54 on the end of the roll 44. A sprocket gear 55 is also provided upon the roll 44 which is connected by a sprocket chain 20 56 with a sprocket gear 57 provided upon the end of the upper roll 48, which in turn is provided with a sprocket gear 58 connected by a sprocket chain 59 to a sprocket gear 60 provided upon the end of the roll 47. This train 25 of gearing rotates the four feed rolls at the same angular speed and in the same direction with respect to each other, the direction of rotation of the feed rolls being reversed during the loading operation with relation to the direction of rotation during the feeding operation.

The apron 61, which is formed of thin muslin or other suitable material, is connected at its ends to the respective rolls 41 and 42 and is 30 adapted to be moved from one onto the other, depending on the direction in which the machine is being driven, being wound on the upper roll during the loading operation of the machine and onto the lower roll during the 35 feeding operation to the ironer. The diameters of the rolls with the apron thereon would thus vary with respect to each other and the center axes of rotation are shifted along a vertical line as the rolls increase or diminish 40 in diameter. This is clearly indicated in Fig. 1 the dotted lines indicating the lowermost positions of the rolls when they are in substantially direct contact with the feed rolls.

In passing between the rolls the apron is 45 extended over a loading and feeding table or support consisting of a frame 62 rotatably supported at its rearward ends upon the upper ends of standards 63 and 64 bolted to the ends of the upper side of the main frame forwardly of the rolls, the apron passing from the lower roll over a guide roller 65 journaled in the standards 63 and 64 at their lower portions, over relatively small diameter rollers 66 provided upon a shaft 67 at the forward end of the frame 62, rearwardly over a roller 68 journaled between the standards 63 and 64 at the rearward ends of the frame 62 and co-axial with the axis of rotation of said frame, and thence to the upper roll 42, pass-

ing between said roll and the feed rollers 48 and 47 as it is wound about said roll 42. As shown in Figs. 8 and 9 the spaced rollers 66 are loosely rotatable upon the tubular shaft 67, which is fixed with relation to the frame 62 and provided forwardly with a series of perforations 69. A compressed air supply line 70 is connected at one end of said shaft and during the feeding operation to the ironer compressed air is admitted to the shaft and is jetted through the perforations to insure removal of the pieces from the apron as they pass into the ironer, the thin muslin of which the apron is formed being sufficiently pervious to permit the air to be blown therethrough. The loading table is counter-balanced so that it may be swung to any desired position, as indicated for instance in dotted lines, Fig. 1, the counter-balance means consisting of weights 71 at each end of the machine slidably suspended upon vertical guide rods 72, supported in spaced relation to the bars 36, upon the ends of cables 73 extending over rollers 74 rotatably mounted at the upper ends of the bars 36, and connected at each side of the frame 62. This counter-balance means permits the table to be swung to any desired position and to be maintained in such position; so that, during the loading operation it may be maintained in a relatively horizontal position, and in the feeding operation it may be adjusted to its proper position in relation to the feeding opening of the ironer.

During loading the machine is operated in a direction to wind the apron from the lower roll 41 to the upper roll 42, the same moving rearwardly along the upper surface of the table 62, while during the feeding operation in relation to the ironer, the machine is rotated in reverse direction. For this purpose a drive shaft 75 for operating the several feeding machines, in their respective loading and feeding positions, is supported beneath the floor in suitable bearing hangers 76 and is continuously driven by means of a belt drive 77, preferably connected (Fig. 4) to the drive pulley of the ironer, so that during the feeding operation to the ironer, the feeder and ironer will be operated in synchronism.

At the intermediate or feeding station in front of the ironer, a gear 78 (Fig. 5) is provided upon the shaft 75 and extends at its periphery through an opening in the floor where it is adapted to mesh with the drive gear 51. The gear 78 is loosely mounted on the shaft, and is adapted to be connected thereto by means of an annularly channeled clutch 79 keyed to the shaft, and adapted to be shifted into engaged or disengaged relation with the gear by means of a forked lever 80 provided on a shaft 81 pivotally mounted in bearings 82, and having a handle 83 extended upwardly through an opening in the floor. The feeding machine is operated con-

tinuously during its feeding relation with the ironer and the lever handle 83 is therefore adapted to remain in either of its moved positions—that is it will remain in clutched relation, when so moved, until it is again moved to unclutched relation.

At each of the loading stations, where the machine is adapted to rotate in opposite direction to its direction of rotation while feeding to the ironer, there is loosely mounted a gear 84 (Fig. 6) which extends through an opening in the floor where it meshes with the drive gear 51, and is provided with a reversed drive mechanism adapted to be 10 clutched to the shaft. This mechanism is mounted in a stationary housing 85 and comprises a beveled gear 86 secured to the shaft 84 and meshes with a pair of beveled pinions 87 and 88 journaled in the housing, and 20 which in turn mesh with a beveled gear 89 loosely mounted on the shaft within the housing and provided with a notched clutch engaging hub portion 90. An annularly journaled collar 91 is slidably keyed upon the 25 shaft and is adapted to be shifted into engaged and disengaged relation with hub 90 by means of a forked lever arm 92 mounted upon a rocker shaft 93 journaled at its ends in bearing brackets 94 secured at the under- 30 side of the floor, and having also secured thereto a lever arm 95 provided with a foot pedal 96 extended upwardly through an opening 97 in the floor and normally pressed upwardly to its clutch disengaging position 35 by means of a spring 98. The machine is therefore normally stationary while the operator places the pieces of laundry upon the apron in as close relation as possible so that substantially the entire area of the apron 40 may be filled to the best advantage and no appreciable ironing space is subsequently wasted in the ironer.

The machine is of such length that a number of operators may be positioned in front 45 of the same during the loading and each kept busy placing the pieces upon the stationary apron. As soon as one portion of the apron is filled the foot pedal 96 is depressed throwing in the clutch 91 and causing the rolls to 50 be turned in clockwise direction so that the apron with the pieces carried thereon is moved into rolled relation about the upper roll 42. The machine is stopped when an 55 unfilled portion of the apron is moved over the frame 62 and this is then filled and the feeding operation repeated. The machine may thus be loaded until the apron is entirely wound from the roll 41 upon the roll 42.

During the loading operation another one 60 of the machines, which has been previously loaded, is stationed in feeding relation to the ironer with its gear 51 in mesh with the continuous drive gear 75, the rolls being rotated in counter-clockwise direction so that the

apron is fed forwardly over the upper side 65 of the frame 62 carrying the pieces into the ironer, this operation continuing until the entire loaded contents of the machine are removed. The feeding and loading operations may therefore be carried on continuously and 70 simultaneously and each with the greatest efficiency, the machine permitting the feeding to the ironer to be carried on continuously and at any desired speed, while the periodical operator controlled operation of the 75 machine during the loading enables the operators to place the pieces in close relation upon the apron and to the best advantage.

In Fig. 7 there is illustrated a modified form of the invention in which a pair of aprons are employed and between the thicknesses of which the pieces are loaded, one of the aprons being in the nature of a covering layer. The main frame is provided at its four corners with upwardly extending standards or posts 100 preferably formed in continuation of the upright corner pieces 32, and the upper channel guides 36 are provided with extension portions 101. The rearward standards support a pair of vertically spaced rolls 102 and 103 journaled thereon, the portions 101 support a roll 104 journaled thereon, and the forward standards are provided with brackets 105 in which are journaled the 85 ends of a roller 106. 90

The covering apron 107 is connected at its ends to the rolls 41 and 42 in a similar manner to the apron 61, and extends from the roll 41 rearwardly over the rolls 102 and 103 and forwardly and downwardly over the rolls 104 and 106 to the roll 42, the roll 106 being so positioned with relation to the roll 68 that the apron 107 converges into contact with the apron 61 as they move into relation with the forward roll 48. 95

During the loading operation the pieces of laundry are assembled, being placed upon the apron 61 as it is in position on the table 62, and as the apron is fed onto the roll 42 the covering apron 107 becomes superimposed upon the pieces. During the feeding operation to the ironers the covering apron prevents any possibility of the pieces sticking to the roll, and in order to insure positive disengagement of the pieces from the underside of the apron 107 a perforated compressed air jet pipe 108 is mounted above said apron between its point of convergence with the apron 61 and the roll 68 and is adapted to jet compressed air through the thin muslin structure of the apron to separate the laundry pieces therefrom. 110

It will be seen that the articles are placed in groups on the feeder apron while the apron is stationary and that when each group has been completed the apron is moved sufficiently to provide for a succeeding group, the groups being positioned substantially 115 120 125

continuously to make up a series of a predetermined number of such groups which is wound up, by the time the last series is completed, into a roll, the articles being in substantially the same relationship in which they were placed on the apron and properly arranged to be fed directly to the ironer without subsequent handling. When the articles to be ironed are handled in the manner hitherto usual, being shaken out and then arranged in piles from which they are taken one at a time and fed to the ironer, certain portions of the articles, being accessible to the air are liable to dry and show as "rough dry" spots in the articles after being ironed. According to the present invention, however, the storage of the articles wound up between the convolutions of the apron acts to "condition" the articles or cause the moisture therein to be substantially uniformly distributed, thus avoiding the presence of dry spots when the articles are fed to the ironer and so avoiding such faulty ironing. Where a plurality of machines are employed it is also apparent that one series of articles is being prepared while another series previously completed is being fed to the ironer.

The articles are fed to the ironer in substantially the same spacial relation as when 30 they are assembled on the feeding apron but in the reverse order.

I have illustrated and described preferred and satisfactory embodiments of my invention but it will be obvious that changes may 35 be made therein within the spirit and scope thereof as defined in the appended claims.

Having thus described my invention, what I claim and desire to secure by Letters Patent is:—

40 1. In a machine of the character described, an apron adapted to have pieces of laundry placed thereon, a roll for receiving said apron with said pieces, whereby the diameter of the rolled apron increases as it is rolled on said roll, constant speed drive means for imparting variable angular and constant surface rotation to said roll and rolled apron in rolling and unrolling directions, said apron adapted to be unrolled in reverse direction to feed 45 said pieces therefrom to an ironer or the like at uniform speed.

2. In a machine of the character described, an apron, a pair of spaced rolls respectively connected to the ends of said apron, means 55 for rotating said rolls whereby the apron is adapted to be wound from one upon the other, a loading and feeding support over which said apron passes in moving from one roll to the other and constant speed drive means for 60 imparting variable angular and constant surface rotation to said respective rolls and rolled apron.

3. In a machine of the character described, an apron adapted to have pieces of laundry 65 placed thereon, a pair of spaced rolls re-

spectively connected to the ends of said apron, constant speed drive means for rotating said rolls and rolled apron at variable angular and constant surface speeds whereby the apron is adapted to be wound from one roll 70 upon the other to store said pieces with the rolled apron upon one of said rolls, said rolls adapted to be rotated in reverse direction to feed said pieces to an ironer or the like at uniform speed. 75

4. In a machine of the character described, an apron, a pair of spaced rolls respectively connected to the ends of said apron, a flat support over which said apron passes in moving from one roll to the other, and constant 80 speed drive means for rotating said rolls and rolled apron at variable angular and constant surface speeds in forward and reverse directions and whereby pieces of laundry are adapted to be loaded at uniform speed on said apron as it is in position on said support and rolled with said apron upon one of said rolls upon rotation of said rolls in one direction, and upon rotation in the other direction to be fed by said apron to an ironer or 85 the like at uniform speed. 90

5. In a machine of the character described, an apron adapted to have movement in forward and reverse directions, means connected to the respective ends of said apron and adapted respectively to receive said apron as it is moved in forward and reverse directions, said apron adapted as it is moved in one direction to have pieces of laundry placed thereon and loaded with respect to one of said means, and adapted as it is moved in the other direction to feed said pieces to an ironer or the like and constant speed drive means for imparting constant speed movement to said apron as it moves with respect to its loading and feeding points. 95 100 105

6. In a machine of the character described, an apron, a pair of spaced rolls respectively connected to the ends of said apron, means for rotating said rolls whereby the apron is 110 adapted to be moved from one upon the other, a loading and feeding support pivotally mounted at its inner end and whereby the outer end is adapted to be swung to variable positions, said apron being adapted to pass 115 over said support in moving from one roll to the other.

7. In a machine of the character described, an apron, a pair of spaced rolls respectively connected to the ends of said apron, means for 120 rotating said rolls whereby the apron is adapted to be moved from one upon the other, a loading and feeding support pivotally mounted at its inner end and whereby the outer end is adapted to be swung to variable 125 positions, said apron being adapted to pass over said support in moving from one roll to the other, and counter-balance means connected to said support and adapted to maintain it in any given position. 130

8. In a machine of the character described, an apron, a pair of spaced rolls respectively connected to the ends of said apron, constant speed drive means for rotating said rolls and 5 rolled apron at variable angular and constant surface speeds whereby the apron is adapted to be moved from one upon the other at uniform speed, a loading and feeding support having a projecting relatively narrow end 10 portion, said apron being adapted to pass about said end portion in flatwise relation over said support in moving from one roll to the other.
9. In a machine of the character described, 15 an apron, a pair of spaced rolls respectively connected to the ends of said apron, constant speed drive means for rotating said rolls and rolled apron at variable angular and constant surface speeds whereby the apron is adapted 20 to be moved from one upon the other at uniform speed, a loading and feeding support having a projecting rollered end portion, said apron being adapted to pass about said rollered end portion and in flatwise relation over 25 said support in moving from one roll to the other.
10. In a machine of the character described, an apron, a pair of spaced rolls respectively connected to the ends of said apron, 30 means for rotating said rolls whereby the apron is adapted to be moved from one upon the other a loading and feeding support having a projecting end portion, said apron being adapted to pass about said end portion and in 35 flatwise relation over said support in moving from one roll to the other, and means adapted to positively disengage pieces of laundry from said apron as it moves in feeding direction about said end portion.
11. In a machine of the character described, 40 an apron, a pair of spaced rolls respectively connected to the ends of said apron, means for rotating said rolls whereby the apron is adapted to be moved from one upon the other, a loading and feeding support having a projecting end portion, said apron being 45 adapted to pass about said end portion and in flatwise relation over said support in moving from one roll to the other, and air jet 50 means adapted to positively disengage pieces of laundry from said apron as it moves in feeding direction about said end portion.
12. In a machine of the character described, 55 an apron adapted to have pieces of laundry placed thereon, a pair of spaced rolls respectively connected to the ends of said apron and constant speed drive means for simultaneously rotating said rolls at equal surface speed whereby the apron is adapted to 60 be moved from one upon the other at uniform speed, said rolls adapted to be rotated in reverse direction to feed said pieces to an ironer or the like at uniform speed.
13. In a machine of the character described, 65 an apron adapted to have pieces of laundry placed thereon, a pair of spaced rolls respectively connected to the ends of said apron, constant speed drive means for simultaneously rotating said rolls at equal surface speed whereby the apron is adapted to be moved from one upon the other at uniform speed, said rolls adapted to be rotated in reverse direction to feed said pieces to an ironer or the like at uniform speed.
14. In a machine of the character described, 70 an apron adapted to have pieces of laundry placed thereon, a pair of spaced rolls respectively connected to the ends of said apron, guides for said rolls whereby they are adapted to have independent bodily movement transversely of their axes, and constant speed drive means for simultaneously rotating said rolls at equal surface speed whereby the apron is adapted to be moved from one upon the other at uniform speed, said rolls adapted to be rotated in reverse direction to feed said pieces to an ironer or the like at uniform speed.
15. In a machine of the character described, 75 an apron adapted to have pieces of laundry placed thereon, a pair of spaced rolls respectively connected to the ends of said apron, vertical guides for said rolls whereby they are adapted to have independent vertical 80 bodily movement transversely of their axes, and constant speed drive means for simultaneously rotating said rolls at equal surface speed whereby the apron is adapted to be moved from one upon the other at uniform speed, said rolls adapted to be rotated in reverse direction to feed said pieces to an ironer or the like at uniform speed.
16. In a machine of the character described, 85 an apron adapted to have pieces of laundry placed thereon, a pair of spaced rolls respectively connected to the ends of said apron and having reduced shaft ends, channel guides for said rolls engaged by said shaft ends whereby said rolls are adapted to 90 have independent bodily movement transversely of their axes, and constant speed drive means for simultaneously rotating said rolls at equal surface speed whereby the apron is adapted to be moved from one upon the other at uniform speed, said rolls adapted to be rotated in reverse direction to feed said pieces to an ironer or the like at uniform speed.
17. In a machine of the character described, 95 an apron, adapted to have pieces of laundry placed thereon, a pair of spaced rolls respectively connected to the ends of said apron, constant speed feed rolls frictionally 100 engaging the cylindrical surface of said spaced rolls, and adapted to be simultaneously driven at equal angular speed and whereby said spaced rolls are simultaneously driven at equal surface speed and the apron is adapted 105 to be moved from one roll upon the other at uniform speed.

uniform speed, said rolls adapted to be rotated in reverse direction to feed said pieces to an ironer or the like at uniform speed.

18. In a machine of the character described, an apron adapted to have pieces of laundry placed thereon, a pair of spaced rolls respectively connected to the ends of said apron, vertical guides for said rolls whereby they are adapted to have independent bodily movement, constant speed feed rolls frictionally engaging the cylindrical surfaces of said spaced rolls and adapted to be simultaneously driven at equal angular speed and whereby said spaced rolls are simultaneously driven at equal surface speed and the apron is adapted to be moved from one roll upon the other at uniform speed, said feed rolls adapted to be rotated in reverse direction to feed said pieces to an ironer or the like at uniform speed.

19. In a machine of the character described, an apron adapted to have pieces of laundry placed thereon, upper and lower spaced rolls respectively connected to the ends of said apron, vertically aligned guides for said rolls whereby they are adapted to have independent bodily movement transversely of their axes, and constant speed drive means for simultaneously rotating said rolls at equal surface speed whereby the apron is adapted to be moved from one upon the other at uniform speed, said rolls adapted to be rotated in reverse direction to feed said pieces to an ironer or the like at uniform speed.

20. In a machine of the character described, an apron adapted to have pieces of laundry placed thereon, a pair of spaced rolls respectively connected to the ends of said apron, a pair of constant speed feed rolls respectively supporting said spaced rolls upon and between them and adapted to be simultaneously driven at equal angular speed whereby said spaced rolls are simultaneously driven at equal surface speed and the apron is adapted to be moved from one upon the other at uniform speed, said feed rolls adapted to be rotated in reverse direction to feed said pieces to an ironer or the like at uniform speed.

21. In a machine of the character described, an apron adapted to have pieces of laundry placed thereon, a pair of spaced rolls respectively connected to the ends of said apron, vertical guides for said rolls whereby they are adapted to have independent bodily movement, pairs of constant speed feed rolls respectively supporting said spaced rolls upon and between them and adapted to be simultaneously driven at equal angular speed whereby said spaced rolls are simultaneously driven at equal surface speed and the apron is adapted to be moved from one upon the other at uniform speed, said rolls adapted to be operated in reverse direction to feed said

pieces to an ironer or the like at uniform speed.

22. In a machine of the character described, a pair of aprons, one constituting a receiving layer for pieces of laundry and the other constituting a covering layer therefor, and means for rolling said aprons with said pieces between them, said aprons adapted to be unrolled in reverse direction to feed said pieces therefrom to an ironer or the like and means for receiving said aprons in superimposed relation as they are unrolled from said first means.

23. In a machine of the character described, a pair of aprons, one constituting a receiving layer for pieces of laundry and the other constituting a covering layer therefor, a pair of spaced rolls respectively connected to the ends of each of said aprons, said aprons adapted to extend in separated relation with respect to each other between said rolls, means for rotating said rolls whereby the aprons are wound from one upon the other to store pieces placed upon said receiving apron between the same and said covering apron upon one of said rolls, said rolls adapted to be rotated in reverse direction to feed said pieces to an ironer or the like.

24. In a machine of the character described, a pair of aprons, one constituting a receiving layer for pieces of laundry and the other constituting a covering layer, a pair of spaced rolls respectively connected to the ends of each of said aprons, said aprons adapted to extend in separated relation with respect to each other between said rolls, means for rotating said rolls whereby the aprons are adapted to be moved from one upon the other to store pieces placed upon said receiving apron between the same and said covering apron upon one of said rolls, and a loading and feeding support over which said receiving apron passes in moving from one roll to the other, said rolls adapted to be rotated in reverse direction to feed said pieces to an ironer or the like.

25. In a machine of the character described, a pair of aprons, one constituting a receiving layer for pieces of laundry and the other constituting a covering layer therefor, means for rolling said aprons with said pieces between them, said aprons adapted to be unrolled in reverse direction to feed said pieces therefrom to an ironer or the like, and means for positively separating the pieces from said covering layer during movement in feeding direction.

26. In a machine of the character described, an apron adapted to have movement in forward and reverse directions, means connected to the respective ends of said apron and adapted to respectively receive said apron as it is moved in forward and reverse directions, said apron adapted as it is moved in one direction to have pieces of laundry

- placed thereon and loaded with said apron in respect to one of said means and adapted as it is moved in the other direction to feed said pieces to an ironer or the like, drive means for continuously moving said apron during its operation in feeding direction, and drive means for moving said apron in loading direction intermittently during operator-controlled periods.
- 10 27. In a machine of the character described, an apron adapted to have movement in forward and reverse directions, means connected to the respective ends of said apron and adapted to respectively receive said apron as it is moved in forward and reverse directions, said apron adapted as it is moved in one direction to have pieces of laundry placed thereon and loaded with said apron in respect to one of said means, and adapted as it is moved in the other direction to feed said pieces to an ironer or the like, forward and reverse drive means for respectively driving said apron during its feeding and loading operations, and means for connecting said reverse driving means intermittently during operator-controlled periods.
- 15 28. In a machine of the character described, an apron adapted to have movement in forward and reverse directions, means connected to the respective ends of said apron and adapted to respectively receive said apron as it is moved in forward and reverse directions, said apron adapted as it is moved in one direction to have pieces of laundry placed thereon and loaded with said apron in respect to one of said means, and adapted as it is moved in the other direction to feed said pieces to an ironer or the like, forward and reverse drive means for respectively driving said apron during its feeding and loading operations, and foot-controlled means for connecting said reverse driving means intermittently during operator-controlled periods.
- 20 29. In a machine of the character described adapted to be moved between loading and feeding stations, an apron adapted to have movement in forward and reverse directions, means adapted to be connected to the respective ends of said apron and adapted to respectively move said apron as it is moved in forward and reverse direction, said apron adapted as it is moved in one direction to have pieces of laundry placed thereon and loaded with said apron in respect to one of said means, and adapted as it is moved in the other direction to feed pieces of laundry to an ironer or the like, drive means located at said feeding station for moving said apron during its operation in feeding direction, and other drive means located at said loading station for moving said apron in loading direction intermittently during operator-controlled periods.
- 25 30. In combination with an ironer, an automatic feeding machine adapted to have move-

ment between a loading station removed from said ironer and a feeding station in contiguous relation thereto, and including forwardly and reversely movable means adapted to have pieces of laundry loaded thereon at said loading station in flat and separated relation, and adapted at said feeding station to automatically feed said pieces to the ironer, and drive means operative at said respective stations for driving said means in forward and reverse directions.

31. In combination with an ironer, a track in front of said ironer and extending at one side thereof, an automatic feeding machine movably mounted on said track adapted to have movement between a loading station removed from said ironer and a feeding station in contiguous relation thereto, and including forwardly and reversely movable means adapted to have pieces of laundry loaded thereon at said loading station in flat and separated relation, and adapted at said feeding station to automatically feed said pieces to the ironer, and drive means operative at said respective stations for driving said means in forward and reverse directions.

32. In combination with an ironer, an automatic feeding machine adapted to have movement between a loading station at one side of said ironer and a feeding station forwardly thereof, and including an apron, forward and reverse drive means for said apron, and a loading and feeding support at the side of said machine toward said ironer and over which said apron passes, and whereby the pieces of laundry are adapted to be placed upon said apron at said loading station as it moves over said support in one direction, and are adapted to be fed by said apron to the ironer as it moves over said support at the feeding station in the other direction.

33. The method which comprises assembling articles to be ironed in close relationship, the parts of each article being arranged suitably for ironing, storing and conditioning the articles so assembled, and then feeding said articles to an ironing machine in the reverse order to their assembly and without disturbing their arrangement.

34. The method which comprises assembling in close relationship, in groups, articles to be ironed, intermittently storing said groups for conditioning of the articles, said groups being close together, and then feeding the articles continuously to an ironing machine while maintaining the same spacial relationship therebetween.

35. The method which comprises assembling articles in close relationship, each article having its parts arranged to be ironed, storing and conditioning the articles, and then feeding the articles to an ironing machine in the same close relationship while the parts of each are maintained in arranged positions.

36. The method which comprises assembling articles in close relationship in a plurality of series, each article having its parts arranged for ironing, storing the articles so arranged for conditioning, and then feeding the articles so assembled to an ironing machine, the articles of one series following substantially continuously the articles of a preceding series, and while the parts of each article are maintained in the same arrangement ¹⁰ as when assembled.
